US00D825134S

(12) **United States Design Patent** (10) **Patent No.:** **US D825,134 S**
(45) **Date of Patent:** **** Aug. 7, 2018**

(54) **SELF-SERVICE TERMINAL**

(71) Applicant: **NCR Corporation**, Duluth, GA (US)

(72) Inventor: **Steven J. Birnie**, Dundee (GB)

(73) Assignee: **NCR Corporation**, Atlanta, GA (US)

(**) Term: **15 Years**

(21) Appl. No.: **29/602,581**

(22) Filed: **May 2, 2017**

(51) **LOC (11) Cl.** **99-00**

(52) **U.S. Cl.**

USPC **D99/28**

(57) **CLAIM**

The ornamental design for a self-service terminal, as shown and described.

DESCRIPTION

FIG. 1 is a perspective view of a self-service terminal showing our new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

1 Claim, 6 Drawing Sheets
